A. C. Burrows, of Providence, R. I.
Letters Patent No. 1023. Dated July 6, 1855.

The schedule referred to in these Letters Patent and making part of the same.

To all persons to whom these presents shall come,

Be it known that I, A. C. Burrows, of Providence, in the County of Providence and State of Rhode Island, have produced a new and original design for a range and I hereby declare that the said new design is fully described and represented in the following description and accompanying drawings, to which reference is herein after made.

The figures of the accompanying plate of drawings represent my new design. Fig. 1. is an elevation of the front plate of the range.

Fig. 2. is a transverse vertical section of the same taken in the plane of the line A-B.

Across the top of the plate is the ornamental leaf-work a.a. and on the bottom the projecting pieces b.b. Each of the oven doors is ornamented with the gothic figures c.c. c.c. corner pieces d.d. and molding e.e. On the sides of the plate are the raised elongated figures, f.f.

Having thus described my new design, I shall state my claim as follows;

What I claim as my invention or production
